UNITED STATES PATENT OFFICE.

JOHN CHARLES FREMONT McCUALEY, OF CROOKED CREEK, KANSAS.

CAR-COUPING.

SPECIFICATION forming part of Letters Patent No. 341,492, dated May 11, 1886.

Application filed March 16, 1886. Serial No. 195,441. (No model.)

To all whom it may concern:

Be it known that I, JOHN CHARLES FREMONT McCUALEY, a citizen of the United States, residing at Crooked Creek, in the county of Ford and State of Kansas, have invented a new and useful Improvement in Car-Couplings, of which the following is a specification, reference being had to the accompanying drawings.

10 My invention relates to an improvement in car-couplings; and it consists in the peculiar construction and combination of devices that will be more fully set forth hereinafter, and particularly pointed out in the claims.

15 Figure 1 is a perspective view of my invention. Fig. 2 is a side elevation of the same. Fig. 3 is an inverted plan view. Fig. 4 is a detail sectional view taken on the line xx of Fig. 3. Fig. 5 is a horizontal sectional view. 20 Figs. 6 and 7 are detail perspective views of the arms e and b , respectively.

This invention is an improvement on the car-coupling described in my application for Letters Patent of the United States, Serial No. 25 187,867, filed November 14, 1885.

A represents the draw-head, which is provided on one side with the vertically-extending mouth B , and which has the central opening, C , for the usual coupling-link, and the 30 laterally-projecting ears D , which extend from the draw-head on the side opposite the mouth B .

In the mouth B is hinged a detent, E , on the lower projecting spindle of which is a coiled 35 spring, F , one end of the said spring being attached in the side of the opening made to receive the spindle, and the other end thereof engaging with an arm, G , which is secured on the lower end of the spindle. This spring 40 keeps the detent normally in the position shown in Fig. 5.

In between the ears D is pivoted a coupling-hook, H —such as described in my application before referred to—the said hook being adapted 45 to enter the mouth B of the opposing coupling and to engage with the spring-actuated pivoted detent therein.

On the under side of the mouth B is secured a casting, I , having rearward-extending diverging arms K , at the inner ends of which

are formed depending-ears L . One of the said ears has a horizontally-extending stud, l . A transverse plate, M , connects the diverging arms near the inner ends of the latter, and on the said plate works a slotted link, N , which is provided on its under side with a ratchet or notch, n . The front end of this link is connected to the outer end of the arm G by means of a chain, O .

P represents a pair of bell-crank levers, 60 which are pivoted on the outer ends of the diverging arms K , and have their inner extending arms connected to the link N by means of rods R .

S represents a rock-shaft having its ends 65 bent downwardly to form arms S' , the said rock-shaft being journaled in horizontal aligned openings that are made in the lower end of the ears L , and to the said shaft is firmly attached a pawl, T , which is adapted 70 to engage the opening n of the link when the latter is moved rearwardly, and the rock-shaft is turned upwardly by means of the mechanism to be hereinafter described.

U and U' represent rods, which have their 75 inner ends attached to the rear extending ends of the bell-crank levers by means of universal joints u . The said rods are also provided near their inner ends with arms u' , which extend at right angles from the rods, and are connected 80 to the arms S' of the rock-shaft S by means of chains u'' . The outer ends of the rods U and U' are bent to form handles, as shown, and the outer end of the rod U is suspended from the front end of the car by means of a cord or 85 strap, V .

When cars provided with my improved form of coupling come together, the coupling-hook H of one coupling enters the mouth B of the other and engages with the spring-actuated detent E 90 therein, and the cars are thus coupled together automatically and without the necessity of a brakeman going between the cars and endangering life or limb. By drawing either of the rods U or U' outwardly from the side of 95 the car, (the said rods being connected to the spring-actuated pivoted detent by means of the bell-crank levers, the sliding link, the arm G , and the chain connecting the link with the said arm, as previously described,) the detent 100

is moved inwardly in the position shown in dotted lines in Fig. 5, and releases the coupling-hook and thus uncouples the car. When it is desired to maintain the detent in this position and thus permit two cars to come together without coupling, as is frequently the case when cars are switched onto or from a siding, the rods U and U', when being drawn outwardly to their full extent, are also turned 10 through about quarter of a circle, causing their arms u' to move rearwardly, and thus draw upwardly on the arms S' of the rock-shaft, which carries the pawl, and thus causes the pawl to engage with the notch n of the link, 15 thus holding the detent firmly in a closed position.

In Fig. 1 I illustrate a mechanism by means of which the cars may be uncoupled by a person on top of one of them. a represents a keeper, which is secured on the front end of the car near one side thereof, and between the said keeper and the end of the car is pivoted an arm, b, the upper end of which is bifurcated, forming a recess or slot, b', and the 20 lower end of the said arm is attached to the rod U' by means of a universal joint, c. An arm, d, is secured to the said rod near the outer end of the latter. e represents a lever-arm, which is pivoted in the upper end of the arm 25 b by means of the bolt f, which forms the fulcrum for the said arm, and the lever-arm e has at its inner end a depending arm, e', which bears against the inner side of the arm b. To the outer end of the lever-arm e is attached a vertical 30 rod, g, by means of a universal joint, g', and the said rod g is guided by means of a keeper, h, on the front end of the car, and extends to the upper side thereof. Near the lower end of the rod g is an arm, g². k represents a bell- 35 crank lever, which is fulcrumed on the outer end of the pivotal bolt f. One arm of this lever is connected to the arm d of the rod U' by means of a chain, k', and the other arm of the said bell-crank lever is connected 40 to the arm g² of the rod g by means of a chain, k². By drawing upwardly upon the rod g the arm U' may be drawn outwardly, and thereby cause the detent E to be swung inwardly in 45 the draw-head to release the coupling-hook,

and by turning the said rod g outwardly 50 through a quarter of a circle, the rod U' (being connected thereto by means of the bell-crank lever and the chains, as hereinbefore described) is caused to partly rotate, thereby causing the pawl to engage with the notch in the link N, 55 as hereinbefore described, thus enabling the car-coupling to be operated by a person on the top of one of the cars.

Having thus described my invention, I claim—

1. The combination, with the draw-head, having the spring-actuated pivoted detent, of the bell-crank lever connected to the said detent, and the rods U and U', attached to the said bell-crank levers, whereby the detent may 60 be moved inwardly against the side of the draw-head by drawing outwardly upon either of the rods U and U', substantially as described.

2. In a car-coupling, the combination of 70 the draw-head having the spring-actuated detent, the bell-crank lever, the rods connected thereto, the link attached to the detent, and having the notch or stop, and the pawl having the arms S', connected with the rods U and U', 75 whereby the detent may be swung inwardly by drawing outwardly on the rods U and U', and locked in that position by partly rotating either of the said rods, to cause the pawl to engage with the notch or stop on the link, for 80 the purpose set forth, substantially as described.

3. The combination, in a car-coupling, of the endwise-moving rod U', for tripping the detent, the levers b and e, for moving the 85 rod, the rod g, jointed to the lever e, the bell-crank lever k, and the chains connecting the arms of the said bell-crank lever with the rods g and U', whereby the rod U' may be partly rotated by turning the rod g, for the purpose 90 set forth, substantially as described.

In testimony that I claim the foregoing as my own I have hereto affixed my signature in presence of two witnesses.

JOHN CHARLES FREMONT McCUALEY.
